C. KROEGEL.

FIRE TRAP DOOR.

APPLICATION FILED OCT. 21, 1914.

1,238,692.

Patented Aug. 28, 1917.

UNITED STATES PATENT OFFICE.

CHARLES KROEGEL, OF OAKLAND, CALIFORNIA, ASSIGNOR OF ONE-THIRD TO ROBERT E. WAINWRIGHT, OF OAKLAND, CALIFORNIA.

FIRE TRAP-DOOR.

1,238,692.

Specification of Letters Patent. Patented Aug. 28, 1917.

Application filed October 21, 1914. Serial No. 867,762.

To all whom it may concern:

Be it known that I, CHARLES KROEGEL a citizen of the United States, residing at Oakland, in the county of Alameda and 5 State of California, have invented certain new and useful Improvements in Fire Trap-Doors, of which the following is a specification.

This invention relates to improvements in 10 self-opening doors particularly adapted to be used in the opening between floors for fire houses. The principal object thereof being to provide a self-opening door, which when opened, is held in a raised position to 15 one side of the opening through which the firemen slide down the pole from one floor to another. The door being held in a raised position there is no chance of the same springing back and injuring persons as they 20 pass through the opening and having no parts which project any distance from the door itself there is no danger of injuries from this cause.

Other objects of my invention are to 25 provide an improved latch mechanism for holding the door in its closed position, the said mechanism being so constructed that it will automatically release the door when a fire alarm is sounded and also to provide means 30 in connection therewith so that in case of failure of the electro-mechanism the latch may be manually released.

Another object of my invention is to provide such a door, which is hinged at one 35 side of the opening only, thus enabling the latter to be freely reached from three sides.

Still another object of my invention is to provide means for setting the latch mechanism after the door is closed.

40 With these and other objects in view my invention consists in the novel construction and arrangement of parts as herein described and pointed out in the appended claims.

45 Reference being had to the accompanying drawing forming a part of this specification,

Figure 1 is a view in section through the opening showing the door in its raised position.

Fig. 2 is a view in section through the opening showing the door in side elevation in its raised position.

Fig. 3 is an enlarged sectional view 55 through the latch mechanism.

Fig. 4 is a sectional view on the line 4—4, Fig. 3.

Fig. 5 is an enlarged sectional view on the line 5—5, Fig. 1.

Referring to corresponding parts by the 60 same numerals of reference, 1 denotes a floor through which is provided an opening 2 having the circular pole 3 in the center thereof down which the firemen slide from the upper to the lower floor. As the upper 65 floor is usually fitted up as living quarters for the firemen while the lower floors are unheated and used to house the fire apparatus, cold air and unpleasant odors ascend through this opening to the living quarters 70 of the firemen.

To prevent this I provide the improved 75 type of door, consisting of the substantially circular portion 4, adapted to fit within the opening 2, and this circular member is provided with a flange 5, which rests on the upper edge of the floor. To the under side of the door arms 6 are attached thereto by means of suitable screws 7, and projecting 80 ends of these arms are provided with eyes 8 by means of which they are pivotally mounted on the shaft 9, which latter is held in a fixed position in brackets 10. A spring 11 provides the necessary power for raising the door, and this spring may be of any 85 preferred type, but as herein illustrated, consists of a coil spring wound right and left handed from the center at which point it is attached to a fixed pin 12 in the shaft 9, the free ends passing under the arms as 90 shown at 13.

At the center of disk 4 is provided a circular opening 14, which fits around the pole 3 and extending from this opening to the edge of the disk is a slot 15, which enables 95 the disk to pass the pole when it is being raised or lowered. This slot is in turn closed by two flaps 16 hinged as at 18 and held in a closed position by means of spring 19.

The latch mechanism consists of a casing 100 20, which is mounted in the side of the opening opposite the hinge of the door. Pending from the under side of this casing are certain supports 21 and 22 through which are slidably mounted the rods 23 and 24. 105 The former is provided with a bolt 25, which is adapted to engage the catch 26 formed on the end of one of the bars 6. The lower rod 24 has attached thereon an arm 27, which extends upwardly and engages a col- 110

lar 28 on the rod 23. The second collar 29 is provided on this rod, which limits the movement of the rod in one direction, the bolt limiting its movement in the opposite direction. Interposed between the arm 27 and the support 22 are springs 30, which urge these rods in a left hand direction, or tend to draw the bolt 25 from the catch 26. This tendency is prevented by means of the latch 31 engaging the notch 32 in the rear end of rod 24. This latch is formed on the end of lever 33, which is pivotally mounted as at 34. A heel 35 is provided on this lever on the opposite side of the pivot from latch 31, this heel being directly under and contacting with the rod 24, and it will be understood that the opening in the support 21 in which rod 24 slides as shown in dotted lines in Fig. 3 is extended upwardly so as 10 to allow the slight raising of the rod. Thus when the lever is turned in a left hand direction the catch 31 is moved downwardly while at the same time the heel 35 moves upwardly thus throwing this end of the rod 20 bodily upward enabling the device to unlatch with a smaller movement of the lever. Movement is imparted to the lever at the rear end either by means of the electro-magnet 37 or by means of a foot press 38. 30 The former acts on an armature 39 attached to lever 33 intermediate its pivotal point and the end thereof, and extending downwardly and to one side so as to come immediately under the core of the electro-magnet. 35 The foot press 38 is slidably mounted in the upper plate of the case 20 and in the angular bent end 22' of support 22, and is urged upwardly by means of spring 39' abutting against 22' and a pin 40. On the under side 40 of 22' is pivotally mounted a small lever 41, one end of which is pivotally attached to the lower end of 38, the other end of which rests against the under side of lever 33. 45 A bellcrank 42 is pivoted to the frame as at 43 and when the device is not set rests in an opening 44 of the case 20. The other end of this bellcrank is provided with a bifurcated end 45, each bifurcation of which is slotted and is adapted to engage a pin 46 50 on the rod 24. The outer end of this bellcrank has an opening 47 through which the finger may be inserted to reset the latch. 55 The operation of the device is as follows:—

When the door is closed in passing the pole 3, the flaps 16 are bent upwardly until the door rests on the floor when these flaps fall by their own weight and close the slot, thus providing a substantially smooth covering for the opening. After the door is 60 closed the finger is inserted through the opening 47 and the bellcrank lever raised, which moves the bar 24 to the right and

through the arm 27 acting against collar 28, the arm 23, causing bolt 25 to engage 65 the catch 26 holding the door closed.

Now, the electro-magnet 37 is so connected that when the alarm gong is sounded current is caused to flow through the winding of this electromagnet, which pulls up 70 its armature 39 moving the lever 33 withdrawing the catch 31 as previously described. In case the electromagnet failed to work the first man to the door would depress the upper end of 38 which through the 75 lever 41 mechanically raises the lever 33 and accomplishes the same results. When this latch is released springs 30 push the bars 23 and 24 to the left disengaging the bolt 25 from its catch and allowing the 80 spring 11 to raise the door. As the door is raised the flaps 16 are pressed downwardly, but as soon as the pole is passed the springs 19 press the flaps upwardly again, thus 85 eliminating the danger of the same being struck by the person sliding down the pole.

It will thus be seen that I have provided an effective device for the purpose mentioned which is automatic in its operation, but in case the automatic means fails to operate the same may be quickly operated 90 mechanically.

While I have shown the preferred embodiment of my invention it will be understood that modifications and minor details 95 in design may be made without departing from the scope of the claims.

What I claim as new and wish to cover by Letters Patent is:—

1. In a closure for the openings between 100 floors of fire houses comprising, a door hinged at one side thereof, spring means for normally holding said door in its open position, a slot extending from the outer edge to center of said door to allow the same to pass the pole through the floor opening, flaps hinged to the side of said slot and means for holding said flaps in the plane of the door when the latter is in its open position. 105

2. In a closure for openings in floors comprising in combination with a pole in the center thereof, a closure having a slot extending from the center to the edge, hinged flaps adapted to close said slot, spring means on the closure for holding said flaps closed but permitting the flaps to open upon engaging the pole and a spring hinge for holding said closure in its open position. 115

In testimony whereof I affix my signature 120 in presence of two witnesses.

CHARLES KROEGEL.
